CLAIM

We claim the ornamental design for a cable with integrated in-line battery, as shown and described.

DESCRIPTION

FIG. 1 is a perspective view of a cable with integrated in-line battery, showing our new design;

FIG. 2 is a top plan view thereof;

FIG. 3 is a right elevational view thereof;

FIG. 4 is a left elevational view thereof;

FIG. 5 is a bottom plan view thereof;

FIG. 6 is a front elevational view thereof; and,

FIG. 7 is a back elevational view thereof.

The broken lines in the drawings illustrate portions of the cable with integrated in-line battery that form no part of the claimed design.
